UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed May 12, 1919. Serial No. 296,640.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to motor-control systems and particularly to systems of the character constituting the subject-matter of my co-pending applications, Serial No. 236,937, filed May 27, 1918, and Serial No. 249,344, filed August 10, 1918.

The object of my invention is to provide an improved motor-control system of the above-designated character.

In application Serial No. 249,344, I have disclosed a few reversing systems for a motor that is controlled according to the systems of application Serial No. 236,937. In all of these systems, the accelerating resistor is controlled by a relay having a coil that is responsive to the voltage drop of a portion or of the whole of the accelerating resistor and by a second coil that becomes energized when the first-mentioned coil becomes de-energized.

According to the present invention, the second-named coil is always energized when the motor circuit is closed. The control system is thereby made neater and the reversing connections are rendered much simpler.

In the accompanying drawings, Figs. 1 and 2 are, respectively, a side and an end elevation of a relay of the type constituting the subject-matter of a co-pending application by R. E. De Camp, Serial No. 241,259, filed June 21, 1918, and assigned to the Westinghouse Electric & Manufacturing Co., which relay is of particular advantage in connection with my invention. Fig. 3 is a schematic view of the circuits of Fig. 4, and Fig. 4 is a diagrammatic view of circuits and apparatus embodying my invention.

As my invention is of particular value in connection with a system employing the De Camp relay above referred to, and illustrated in Figs. 1 and 2, it will conduce to clearness to describe this relay first.

An insulating panel 29 carries two brackets 30 and 31 supporting the coils 22 and 23 which, when energized by current flowing through them, create magnetic fields

for attracting an armature 32 and any desired number of additional armatures 33. A compression spring 36 is adjustably mounted upon a non-magnetizable rod 37, slidably mounted in projections 38 and 39, which are rigidly connected to, or constitute integral parts of, the bracket 31. A non-magnetizable guide member 72 is provided in the projection 38 for the rod 37. The projection 38 serves also as a pole piece for the armature 32 and the projection 39 as a pole piece for the armatures 33. A bar 40 is rigidly connected to the rod 37 and normally engages the armatures 33. The spring 36 thus normally maintains the armatures 33 in their open positions, with the members 41, which are carried by these armatures, in contact with the pole piece 39. The members 41 are preferably of non-magnetizable material to prevent "freezing".

The armature 32 is provided with brackets 42, which are pivotally mounted upon the bracket 30, and is normally maintained in contact with one end of the rod 37 by a weak spring 43. A magnetizable member 71 is mounted upon the projection 38 for distributing the flux that is adapted to energize the armature 32, thus rendering the armature 32 more sensitive to current changes. The bracket 30 supports a non-magnetizable U-shaped member 44 between the arms of which are pivotally mounted the armatures 33, which carry, respectively, the movable contact members 45, 46 and 47 of relays 25, 26 and 27. The corresponding stationary contact members 48, 49 and 50 are mounted upon the insulating panel 29.

Springs 51 are attached to longitudinally adjustable members 52 and to the other ends of the members 41. The pole piece 39 is provided with longitudinally adjustable members 53 to regulate air gaps 70 between these members and the corresponding armatures. By means of this adjustment, or by means of the members 52, which control the tension of the springs 51, the action of the magnetic flux produced by the coils 22 and 23 may be so regulated that the armatures 33 will be operated in proper sequence.

The operation may be briefly described as follows: upon current flowing through the coil 22, a magnetic field is created which causes the armature 32 to be attracted to-

ward the pole piece 38. The force of the spring 36 is thereupon overcome, and the bar 40 is moved out of engagement with the armatures 33, the stop members 41 of which are, nevertheless, maintained in engagement with the pole piece 39 until the flux of the magnetic field becomes successively sufficiently low to permit the springs 51 to successively actuate the movable contact members 45, 46 and 47, thereby to close the relays 25, 26 and 27. In the event that the magnetic field becomes too weak to hold the armature 32 in its elevated position, the spring 36, becoming released, will separate the movable 15 from the stationary contact members.

Turning now to Fig. 4, a motor, having an armature 1, a shunt field-magnet winding 2 and a series field-magnet winding 84, is connected between line conductors 3 and 4 20 by a main knife switch 76. An accelerating resistor 6 is provided in series with the armature 1. The direction of rotation of the motor is controlled by pairs of reversing contactors 58 and 61 and 59 and 60 that 25 are respectively controlled by actuating coils 62 and 63 and are provided with mechanically connected switches 66 and 67 that are open when the reversing switches are closed and closed when the reversing 30 switches are open. The circuit of the motor is controlled also by a line contactor 5 having an actuating coil 8.

A plurality of contactors 10 and 11 (only two are illustrated) are adapted to effect the 35 short-circuiting of successive sections 13 and 14 (but two are shown, for purposes of illustration) upon being actuated to closed position by coils 19 and 20, the circuits of which are respectively controlled by the relays 25 and 26. In order to simplify the drawings, I have shown but two relays in the system 40 of Fig. 4. The coil 22, which controls the relays 25 and 26, is connected in circuit with a resistor 86 across the resistor 6 at the junction points 79 and 80 and the coil 23 is connected to the line conductors 3 and 4 in circuit with the resistor 24, through a master switch 7 and a knife switch 77, which are adapted to control the control circuits.

50 A dynamic-braking circuit for the motor is adapted to be established through a dynamic-braking resistor 74 upon the closing of the switches 66 and 67, which switches are adapted to be maintained closed, so long as the counter-electromotive force of the motor exceeds a predetermined value, by coils 78 and 81. A no-voltage relay 73 and an overload relay 75 are provided, the coil of the no-voltage relay being adapted to be 55 energized through the master switch 7 which controls also the circuits of the coils 8, 23, 62 and 63, as will appear hereinafter.

Assuming that the knife switch 77 is closed and that the master switch 7 has been 60 actuated to its first position *a*, either to the

right or to the left, a circuit is established from the line conductor 3, through the knife switch 77, to a stationary contact member 9^a of the controller 7 and from there, through the controller 7, to a stationary contact member 9 and thence, through the actuating coil of the no-voltage relay 73, the overload relay 75 and the knife switch 77, to the line conductor 4. The no-voltage relay 73 becomes thereupon closed by its actuating 70 coil, and a holding circuit for the coil is established from the line conductor 3 through the knife switch 77, the no-voltage relay 73 and its actuating coil, the overload relay 75 and the knife switch 77, to the line conductor 4. The circuit through the contact member 9^a is broken when the master switch 7 is moved from the position *a* but the no-voltage relay 73 will be maintained closed by the above-traced holding circuit 80 so long as the conductors 3 and 4 are supplied with voltage or until the overload relay 75 becomes opened by overload conditions.

Assuming that the master switch 7 is actuated to its second position *b*, let us say to the left, a circuit becomes established from the line conductor 3, through the knife switch 77, the no-voltage relay 73, the stationary contact members 9 and 16—which are bridged by the master controller 7, in the position *b*, the coils 63 and 8 and the knife switch 77 to the line conductor 4. A circuit is also established for the coil 23 in series 100 with the coil 63 and in parallel to the coil 8, the circuit extending from the contact member 16, which is connected to the line conductor 3, through the coil 63, the resistor 24, the coil 23 and the knife switch 77, to the line conductor 4. The coil 63 is thus energized to effect the closing of the reversing contactors 59 and 60 and the opening of the switch 67. The line contactor 5 is closed by its coil 8, and the armature 32 (Fig. 1) 105 is actuated into engagement with the magnetizable member 71 by the coil 23 to effect the release of the armatures 33 from their engagement with the bar 40, in opposition to the force of the spring 36.

Assuming that the knife switch 76 is also closed, a circuit may now be traced from the line conductor 3 through the knife switch 76, one of the coils of the overload relay 75, the reversing contactor 59, the armature 1, the reversing contactor 60, the series field-magnet winding 84, the junction point 80, the resistor 6, the junction point 79, the line contactor 5, the other coil of the overload relay 75 and the knife switch 76, to the line conductor 4. The circuit of the shunt field-magnet winding 2 becomes immediately established upon the closing of the knife switch 76 by a circuit extending from line conductor 3, through the first-named coil of the overload relay 75, the 110 120 125 130

shunt field-magnet winding 2, the other coil of the overload relay 75 and the knife switch 76, to the line conductor 4.

The motor circuit is thus established for 5 operation of the motor in one direction. The coil 22, which is subjected to the voltage drop across the junction points 79 and 80 of the resistor 6, is energized to aid the coil 23 in maintaining the armature 32 in its 10 actuated position and to maintain the armatures 33 in such positions that the members 41 are in engagement with the pole piece 39, so that the relays 25 and 26 are maintained open. As the motor accelerates and the 15 current traversing its circuit decreases, in consequences, the voltage drop of the resistor 6 becomes decreased so that the spring 51, which is attached to the armature 33 of the relay 25, will effect the closing of this armature in opposition to the forces of the magnetic fields of the coils 22 and 23, thereby 20 effecting the closing of the relay 25.

Assuming now that the master switch 7 has been actuated to its third position *c*, a 25 circuit becomes established from the contact member 9, which is connected to the line conductor 3, by the no-voltage relay 73, through the master switch 7, the contact member 18, the coil 19, the contact members 30 48 and 45 of the relay 25, the junction point 79, the line contactor 5, one of the coils of the overload relay 75 and the knife switch 76, to the line conductor 4. The contactor 10 becomes thereupon closed by its actuating coil 19 to effect the short-circuiting of the resistor portion 13.

As the motor continues to accelerate, the 40 voltage drop across the remaining portion of the resistor 6 will become further decreased until, ultimately, the spring 51, which is connected to the armature 33 of the relay 26, will effect the closing of this second relay in opposition to the force of the magnetic fields of the coils 22 and 23. 45 A circuit then becomes established through the coil 20 and the relay 26, in parallel to the coil 19 and the relay 25, whereupon the contactor 11 becomes closed by its actuating coil to effect the short-circuiting of the remaining portion 14 of the resistor 6. The 50 motor will now operate at its normal speed.

Upon the short-circuiting of the entire resistor 6, the coil 22 becomes, of course, de-energized, but the coil 23, if properly de- 55 signed, will maintain the armature 32 in engagement with the magnetizable member 71 to maintain the armatures 33 released from the control of the bar 40 (Fig. 1) but will not effect the reclosing of the armatures 60 33 in opposition to the forces of the springs 51. The motor, therefore, will continue to operate at normal speed.

If the master switch 7 be returned to the 65 position *b*, the circuits of the coils 19 and 20 will become reopened and the resistor 6

will become reinserted into the armature circuit. If the master switch 7 be returned to the position *a*, or if the no-voltage relay 73 becomes opened by the low voltage conditions, or if the overload relay 75 becomes opened, the coil 63 will become de-energized, whereupon, the reversing contactors 59 and 60 will fall open by gravity and the switch 67 will become closed. A dynamic-braking circuit for the motor will then be established from one brush of the armature 1 by a conductor 82, through the switch 67, the dynamic-braking resistor 74, the switch 66 and by a conductor 83, to the other brush of the armature 1. During the dynamic-braking operation, the switches 66 and 67 will be maintained closed not only by gravity but also by the coils 78 and 81, respectively, which are maintained energized in accordance with the voltage drop across the dynamic-braking resistor 74. When the voltage across the resistor 74 falls to a sufficiently low value, the coils 78 and 81 will not be very strongly energized and it will be possible to establish the motor circuit 90 for operation in the same or in the reverse direction upon energization of the coils 63 and 62, respectively, in accordance with the position of the master switch 7.

To operate the motor in the reverse direction, the master switch 7 will be actuated to the right; the operation will be substantially the same, the only difference being that, instead of the coil 63 being energized through the contact member 16, the coil 62 will be energized through the contact member 17. The reversing contactors 58 and 61 will become closed to establish the motor circuits for operation in the reverse direction. The accelerating and the dynamic-braking operations are substantially the same as those above described.

The novelty of the present invention, specifically stated, resides, therefore, in so connecting the coil 23 that it will be maintained energized during the accelerating operation, so that the necessity for inserting a coil into circuit to take the place of the coil 22 upon the short-circuiting of the resistor 6, as is done in my above-mentioned 115 co-pending applications, is avoided.

I claim as my invention:

1. The combination with an electric circuit, of a switch for controlling said circuit, and a relay for controlling said switch, said switch comprising actuating means therefor and said relay having means comprising a pair of assisting coils for controlling the effectiveness of said actuating means, one of which is controlled in accordance with the electrical conditions of a portion of said circuit and the other of which is energized in accordance with line voltage whenever said circuit is closed.

2. The combination with an electric motor 130

- and a source of energy therefor, of means comprising a switch for controlling said motor, and a relay for controlling said switch, said switch comprising actuating means therefor and said relay having a pair of assisting controlling coils one of which is controlled in accordance with the drop in potential across a portion of said circuit and the other of which is connected to said source and energized in accordance with the voltage thereof whenever the circuit of said motor is closed.
3. The combination with an electric motor, a resistor in series therewith, and a source of energy for said motor, of means comprising a switch for controlling said resistor, said switch comprising means for actuating it to its closed position and having, also, a pair of assisting coils one of which is controlled in accordance with the drop in potential across said resistor, and the other of which is connected to said source and is energized in accordance with the voltage thereof.
- 25 4. The combination with an electric motor having a resistor associated therewith and a source of energy for said motor, of means comprising a switch for controlling
- said resistor, said switch comprising means for biasing it to its closed position and having a pair of assisting controlling coils one of which is connected across said resistor and which, when energized below a predetermined degree, permits said switch to close, and the other of which is connected to said source for energization thereby and must be energized prior to the closing of said switch.
5. The combination with an electric motor and a resistor in circuit therewith, of means for controlling said resistor comprising a switch, means tending to close said switch, and means for controlling said closing means comprising a coil energized in accordance with line voltage while the motor circuit is closed and a coil for assisting the first-named coil and that is energized in accordance with the drop in potential across said resistor, which, when energized below a predetermined degree, permits said switch to close.

In testimony whereof, I have hereunto subscribed my name this 30th day of April 1919.

HENRY D. JAMES.
